UNITED STATES PATENT OFFICE.

HEINRICH TOLLE, OF VILLINGEN, BADEN, GERMANY, ASSIGNOR TO DEUTSCHE HOLLERITH MASCHINEN GESELLSCHAFT M. B. H., OF BERLIN, GERMANY, A GERMAN CORPORATION.

PRINTING TABULATING MACHINE.

Application filed May 18, 1923. Serial No. 639,832.

To all whom it may concern:

Be it known that I, HEINRICH TOLLE, a citizen of Germany, residing at Villingen, Baden, Germany, have invented certain new and useful Improvements in Printing Tabulating Machines, of which the following is a full, clear, and exact description.

This invention relates to a computing machine in which the setting or adjustment 10 of the counters is effected by reciprocating toothed racks. The invention has for its object to provide such counter operating mechanism with reciprocating racks, which will be accurate and positive in operation and at 15 the same time present a compact structure. It is necessary for this purpose that the counter operating toothed racks are maintained free from all the laterally extending projections thereon. In accordance with 20 this invention this result is achieved by actuating the toothed racks for individual computations through the intervention of oscillating latches which are caused to mesh at different phases of their oscillatory movement, so that, depending on the particular 25 time of enmeshment of the latches the toothed racks will move through a longer or shorter path and will thereby impart to the counters a correspondingly larger or 30 smaller movement of rotation.

For printing sums and for resetting the counter wheels to zero a special arrangement is required, which, taking into consideration the compactness of the entire 35 structure, must be of such nature that the actuating mechanism for the toothed racks will take up no more space in a transverse direction than the toothed racks. In the improved machine this condition is met by 40 providing a system of pusher bars or rods in extension of the setting toothed racks for actuating said racks for the sum printing operation and for re-seating the counters to zero position.

Fig. 1 is a sectional view of the complete machine taken just inside one of the side plates thereof.

Fig. 2 is a similar sectional view with parts omitted in order to more clearly show 50 the operation of the adding and tabulating parts of the machine.

Fig. 3 is a sectional view showing the operating parts utilized in taking sub-totals or intermediate totals.

Fig. 4 is a sectional view showing the 55 operation of the parts when the machine is to be cleared after a total has been taken.

Figs. 5 and 6 are enlarged detail views showing the latch mechanism for the racks respectively in latched and unlatched po- 60 sition.

Fig. 6 shows the unlatched position of the parts just after a rack has been set by the latching devices.

It will be understood that the machine 65 can include any number of accumulating sections, in which case these sections will be identical in construction. For each section of the machine there are three operating keys designated respectively 29^a, 29^b and 70 29^c. Key 29^a is utilized for setting the machine in operative condition for straight adding. Key 29^b is a sub-total key, which is depressed at the end of the addition of items from a group of cards to cause the 75 machine to take a sub-total and then go on accumulating without clearing the counter. Key 29^c, on the other hand, is a total key. It is depressed at the end of the addition of a group of cards to cause the machine to 80 print a total and cause the accumulator to be cleared. Inasmuch as the accumulating mechanism on the different sections is identical one section alone will be described, it being understood that duplicate mechanism 85 will be provided for the other accumulating sections or in case the machine includes only one accumulating section only one set of parts will be needed.

The tabulating machine comprises two 90 side plates and the adding mechanism is built in therebetween. This is shown in Fig. 1 of the drawings, one of the side plates being removed for the purpose. The adding mechanism is arranged on the side 95 plate 1 shown in the drawings and comprises a stationary plate 2 and a movable slide 3 thereon. The plate 2 carries the tens-counting mechanism control and consists mainly of the control levers 4, release 100 lever 5, arresting lever 6, and the lifting lever 7. The counter rollers 8 and their actuating wheels 9 and 10, as well as the release lever 11, the safety locking lever 12 are arranged on the slide 3. The latter 105 may be raised by the lever 13 through the intervention of the projection or abutment 14, when a dog member 16 resiliently se-

2

cured to the lever 13 is set by the key 29^a (Fig. 2) through the rod 15, in such manner that in its upward movement the dog member 16 will carry along with it the projection 14 on the slide 3. In addition to the lever 13 there is provided another lever 18 (Fig. 4) similar in its function to the lever 13 but controlled by a differently shaped cam disc 19 and consequently operating at different times from the lever 13 to raise and lower the slide 3. The dog member 18^a of the lever 18 is actuated from a special bar or rod 20 through the intervention of a key 29^b (Fig. 4). In addition to the rods 15 or bars 15 and 20, other bars or rods 23 and 24 operate in the same guide bearings 21 and 22 (Figs. 1 and 3). Bar or rod 23 (Fig. 1) carries at its right a roll 26 which may drop into a notch formed in a crank disc 27. When this notch is reached bar or rod 23 is moved to the right under the influence of spring 28^a and the locking hook 28 having a fork and pin coupling therewith releases the key levers 29, 29^a, 29^b. The reference character 29 refers generally to the key levers. These are given further detail reference letters 29^a, 29^b, or 29^c depending upon their function. The key levers are however maintained in the depressed position by means of beveled locking members 30, 30^a, 30^b, 30^c rotating simultaneously about a shaft 25. In view of the simultaneous operation of the locking members 30, 30^a, etc., the depression of a new key releases all previously depressed keys. The bar 24 (Fig. 3) carries a pin 31 and transmits the pressure of the key 29^b, through the intervention of a lever 32 and rod 33, to a bell crank lever 34 which is adapted to engage a pin in the slide 3 and to raise the adding mechanism. In this position the wheel 10 engages a toothed bar or rack 35, which by means of a pin 36 sets the type segments 52, which latter may be locked prior to printing by a lever 37. A special arm on this lever places a colored ribbon in front of the types, by means of a rod 38, while said types are being set. The lever 37 is actuated through the intervention of the intermediate lever 39 from the bell crank lever 40, which is in turn operated by the specially formed cam disc 62. The toothed bar or rack 35 receives its movement from the reciprocating carriage 41, the latter being actuated from the cam disc 42 through the intervention of the large bell crank lever 43. The coupling of the carriage 41 and the toothed rack 35 is effected by the multi-toothed locking hook 44 which is adapted to be actuated by magnets 47 through the intervention of levers 45 and 46 to engage the teeth of the rack 35. In extended alignment with the rack 35 is arranged a rod 48 under the influence of a spring 49 and adapted to be held back by an arresting or locking lever 50, until released by the depression of predetermined keys 29 and 29^b. This movement of the lever 50 is transmitted (by a through setting rod 51 passing along side of the rods 48 and 35) to a type segment similar to and adjacent the type segments 52, which segment then causes the printing of an indication of the manner of use for which the machine was set. In view of the different distances between the points of engagement of the rods 53 and 54 and the centre of rotation of the keys, the lever 50 moves differentially to control the rotation of the type segment and thereby differentiates the various settings of the machine such as the indication of sub and grand totals. The spring bars or rods 48 are returned upon completion of their operative movement to their original positions by the carriage 41 through the aid of the lever 55 rotatably mounted on the carriage 41 and moving in an additional path by the sliding of its inclined surface on the pin 56. The rods or levers 57, 58, 59, 60 serve to withdraw after each excitation of the magnets 47 such armatures as may cling to the magnets. This rod or lever system is actuated from a pin on the lever 13.

The operation of the tabulating machine in its various individual uses is as follows:

1. Adding and tabulating (Fig. 2).

When the key 29^a is depressed the rod 15 moves to the right. The dog member 16 is thereby swung upward and is positioned under the projection or abutment 14 of the counter mechanism slide 3. If the machine is now operated the two cam discs 42 and 61 will rotate in the direction indicated by the arrows, on a ratio of one to one. In this manner the roll of the bell crank lever 43 is moved downwardly and the carriage 41 is thereby moved from left to right. At the same time a contact is closed in known manner (see Hollerith Patent No. 945,236, dated January 4, 1910) in the card feeding arrangement, which contact is held closed while a card is passing through the machine. When a counting position or perforation is reached in the card the circuit of one of the magnets 47 will be completed (as in Hollerith) and the carriage 41 coupled with one of the rack bars 35. Each magnet for a corresponding card column is held energized while counting takes place as is usual. The movement of the armature of the magnet 47 is transmitted through the levers 46, 45 to the coupling member 44 which engages the rack 35 and carries the same along through a path the extent of which depends on the position of the counting point or perforation in the card. During this forward movement the rack 35 effects the setting of the type segment 52, through the intervention of the pin 36.

After the carriage 41 has completed its movement to the right, the lever 37 which has to this moment been kept out by the levers 39 and 40 and by the cam disc 62 (Fig. 3), is now released for a short period. The type segment 52 is thereby centralized to effect proper alignment of the type, and the colored ribbon rod 38 moves the colored ribbon to the left in Fig. 1 to the type. At this moment the type is printed in known manner on a passing paper sheet. In the meantime also the cam disc 61 (Fig. 2) has begun to lift the lever 13 and has thereby caused the engagement of the intermediate wheel 10 and the toothed rack 35, while the roll of the bell crank lever was passing over a concentric portion of the cam 42, thereby maintaining the racks 35 at rest for printing. This movement of the lever 13 is transmitted through the system of rods or levers 60, 59, 58, 57 to the lever 45 and the coupling between the members 44 and 35 is thereby released. This step is taken to ensure that no armature clings to an electro-magnet after the circuit of the magnets is broken. The carriage 41 now moves idly back a certain distance under the action of the rising part of the cam disc 42, such distance corresponding to the complementary number of the perforation in the card column. The shoulder of the coupling member 44 thereby engages the projection on the rack 35 and returns the rack to its zero position. In this manner the same number is transferred to the adding roll 8. If now the number 9 is exceeded, the tens-arrangement is brought into operation under the influence of the release levers 11 and 5, and its operation is completed upon the return of the adding mechanism to rest.

The machine is thus returned to its original position and begins addition and tabulation of the next card column.

If a contact arrangement is used which in place of the time contact, such as assumed above, establishes a momentary contact, i. e., one which differentiates the numbers not by the duration of the current impulses but by closing the contacts at different times, and in which the duration of individual contacts may be less than the time necessary for effecting the registry of a unit in the counter mechanism, such modification is taken care of by the provision of arresting or locking levers 69 (Figs. 5, 6), the arrangement being such that the coupling between the rack 35 and carriage 41 is maintained until the latter has completed its operative movement.

The operation is then, as follows: If the coupling member is actuated by the magnet 47 through the aid of the intermediate lever 45, the latter is prevented from dropping by the lever 69 (Fig. 5), until the carriage 41 has completed its movement to the right.

At that moment the pin 70 secured to the carriage 41 releases the lever 45 (Fig. 6), and the arrangement is prepared for a new contact.

2. Printing of intermediate totals (Fig. 3).

The machine has added a row of numbers and is restrained by a stop cam or has been brought to rest by the completion of the computing operation. Upon depression of the key 29^b the rod 24 is moved to the right. This movement on the one hand, couples the adding mechanism with the toothed rack 35, and, on the other hand, it locks the levers 45 through the intervention of the upper nose of the lever 32, thereby preventing the engagement of the couplings 44 through accidental current impulses. The depression of the key also causes the lever 50 to move outwardly and thereby to release the spring bars 48. The latter now follows the left to right movement of the carriage 41 caused by the rotation of the cam disc 42. The racks 35 are next brought to the position with their projection 63 bearing on the couplings 44 and they rotate the adding wheels 10 backwards until the noses thereof lie against locking hooks, i. e., until the adding mechanism is brought to the zero position. The carriage 41 then completes its movement idly. The movement of the racks 35 also causes the type segments to be set so that the printing may now be effected in the usual manner. The rising part of the cam disc 42 carries the racks 35 back and thereby brings the previous sum back to the adding mechanism. In view of the sliding of the inclined face of the lever 55 (Fig. 4) on the pin 56, the pin 64 moves through a longer path than the carriage 41 and thereby releases the bars 48 from the rack 35. The machine remains at rest in this position and is ready to perform other functions.

3. Totalizing and zeroizing of the counter mechanism Fig. 4.

If it is desired to print the total at the end of a column and to cancel the sum in the adding mechanism, so that the latter may be ready to perform a new addition, the operation of the machine is similar to that for taking intermediate sums, except that the coupling between the toothed rack and the counter roll is released when the latter is in the zero position. In this operation, steps must be taken to prevent the toothed racks, which are suddenly released and which are under the influence of the spring 49, from accumulating the complementary numbers of the sum. The timely release of the engagement between the toothed rack 35 and the toothed wheel 10 is effected not by the release of the keys proper, as in the printing of intermediate sums, but, as in the adding operation, the key 29^c causes the rod 20 to

move to the right and the lever 18 is pushed under the post 17, whereby, in the continued operation of the machine, the cam disc 19 immediately causes the engagement 6 of the toothed wheel 10 and rack 35, which engagement is maintained until the carriage 41 has completed its movement to the right. By the displacement of the rod 20 the lever 57 is pressed against the lower projection 10 of the lever 45 holding the latter back. As the toothed racks 35, which are under the influence of the spring 49 and which until now have been restrained by the toothed wheels 10 (which latter have rotated until 15 their noses rest on the locking hook 12), might accumulate the complementary member of the last sum upon the release of the engagement between the wheel 10 and the rack 35, the locking hook or latch 65 is allowed to be pulled down (through the shifting of rod 15' to the left by the crank wheel 67) shortly before the wheel 10 is disengaged from the rack (and while the carriage 41 changes the direction of its movement) and drops in the notch of the toothed rack 48 (which lies directly under the point of the hook) thereby holding the rack 35 from the influence of the spring 49. The hook was until then maintained in inoperative 20 position by the cam disc 68, through the intervention of the return of the toothed rack 35 and of the spring 49 is effected in a similar manner as in the printing of intermediate sums, by the coupling bars 44 and 25 the lever 55. The machine is thereby returned into its original position.

Claims.

1. A tabulating machine provided with reciprocating racks, adding mechanism, and 40 printing devices, and including in combination a plurality of actuating devices for the racks, one of said devices including reciprocating latches which are adapted to be coupled with the racks for a particular setting, 45 another of said devices including pusher bars which actuate the racks only when the said racks are disengaged from the reciprocating latches.

2. The invention set forth in claim 1 in 50 which the means for engaging the latches with the racks comprises members on which the latches are adapted to slide while in operation.

3. The invention set forth in claim 1 in 55 which the means for coupling the latches with the racks includes members, electro-magnetic means controlled by a momentary

contact for operating said members and latches for locking said members in operative position.

4. The invention set forth in claim 1 in which the means for coupling the latches with the racks includes electro-magnetically operated members and in which means is provided for positively restoring said members to normal position upon the completion of the setting of the racks.

5. The invention set forth in claim 1 in which means is provided for positively restoring the racks and pusher bars to normal 70 position after the racks are uncoupled from their latches, and in which means is provided for thereafter retaining the pusher bars in restored position.

6. In a printing tabulating machine, in 75 combination with a printing element, a registering element, a common actuating member 35 therefor, means adapted to move synchronously with the movement of a card through the machine for controlling the operation of the common actuator, and electro-magnetically controlled means called 80 into action by a perforation in the record card for determining the extent of movement of the common actuating member.

7. In a printing tabulating machine, in combination with type elements, accumulating mechanism, reciprocating racks, each of which is common to a group of type elements and a corresponding element of the 90 accumulator for setting the same, means adapted to move synchronously with the movement of a card through the machine for controlling the operation of the common actuating racks, electro-magnetically 95 controlled means called into action by a perforation in the record card for determining the extent of movement of the common actuating racks and their cooperating type and accumulator elements.

8. In a printing tabulating machine, in combination with a printing element, a registering element, a common actuating member 35 therefor, means adapted to move synchronously with the movement of a card 105 through the machine for moving the common actuator, and electro-magnetically controlled means called into action by a perforation in the record card for coupling the synchronously operated means with said 110 common actuating member.

In testimony whereof I hereto affix my signature.

HEINRICH TOLLE.
